US00D817670S

(12) **United States Design Patent** (10) Patent No.: **US D817,670 S**
(45) Date of Patent: **** May 15, 2018**

(54) **COLOR CENTER DISPLAY**

(71) Applicant: **Behr Process Corporation**, Santa Ana, CA (US)

(72) Inventors: **Mark Germain**, Long Beach, CA (US); **Diana Olvera**, Santa Ana, CA (US); **Miguel Anaya**, Pleasanton, CA (US)

(73) Assignee: **Behr Process Corporation**, Santa Ana, CA (US)

(**) Term: **15 Years**

(21) Appl. No.: **29/592,385**

(22) Filed: **Jan. 30, 2017**

(51) LOC (11) Cl. **06-06**

(52) U.S. Cl.

USPC **D6/675.4**

Primary Examiner — Kelley Donnelly

(74) Attorney, Agent, or Firm — Lora J. Graentzdoerffer

(57) **CLAIM**

The ornamental design for color center display, as shown and described.

DESCRIPTION

FIG. 1 is a perspective view;

FIG. 2 is a front elevation view;

FIG. 3 is a rear elevation view;

FIG. 4 is a right side elevation view;

FIG. 5 is a left side elevation view;

FIG. 6 is a top plan view; and,

FIG. 7 is a bottom plan view.

The broken-line disclosure in the views represents portions of the color center display in which the claimed design is embodied, but which forms no part of the claimed design.

1 Claim, 5 Drawing Sheets
